UNITED STATES PATENT OFFICE.

FREDERICK WILLIAM REED, OF SOUTH BEND, INDIANA.

EMBOSSING ATTACHMENT FOR PRINTING-PRESSES.

1,268,618.

Specification of Letters Patent.

Patented June 4, 1918.

Application filed October 1, 1914. Serial No. 864,492.

To all whom it may concern:

Be it known that I, FREDERICK W. REED, a citizen of the United States, residing at South Bend, in the county of St. Joseph and State of Indiana, have invented certain new and useful Improvements in Embossing Attachments for Printing-Presses, of which the following is a specification.

My invention relates to embossing attachments for printing presses, and more particularly to an embossing die heating plate adapted to be attached to the bed of a printing press, and its object is to provide a device of this character which will be cheap in construction, effective in operation, which may be mounted in the chase and attached to the bed of the printing press without altering the same in any way, and to provide the device with certain new and useful features hereinafter more fully described, and particularly pointed out in the claims.

In the process of embossing, it has been found desirable to have one of the embossing dies heated, preferably the female die, as this prevents the paper from cracking and tearing when it is pressed between the dies. It has been common practice to provide an embossing press built especially for this kind of work, in which the bed of the press is adapted to be heated by convenient means and the embossing die clamped to the bed receives the heat therefrom. These machines are necessarily expensive, and because of their expense they can only be afforded by firms doing a large business. Furthermore, it is wasteful to heat the entire bed of the printing press when only a small embossing die is used thereon.

This invention is adapted to overcome the above-mentioned objectional features by providing an embossing die heating plate in which is embedded electric heating elements by which the plate may be heated by any convenient electric current, such as an electric light current, and this plate is provided with means for attaching an embossing die to its surface. The combined plate and die are of a thickness equal to the height of ordinary type and the plate may be mounted in the chase of the printing press and attached to the bed thereof without any alteration of the same.

Another object of the invention is to provide an embossing die heating plate embodying among other characteristics features

whereby neither the plate nor the bed of the printing press will become unduly heated, and whereby the die may be properly heated expeditiously with a maximum amount of heating medium.

With the above and other objects in view, the present invention consists in the combination and arrangement of parts, herein-after more fully described, illustrated in the accompanying drawings and particularly pointed out in the appended claims, it being understood that changes may be made in the form, proportion, size and minor details without departing from the spirit or sacrificing any of the advantages of the invention.

In the drawings:—

Figure 1 is a top plan view of my embossing plate showing the same locked within the chase.

Fig. 2 is a bottom plan view thereof showing the same removed from the chase and with the filling element removed to illustrate the manner of wiring.

Fig. 3 is an enlarged longitudinal view taken on the line 3—3 of Fig. 2.

Fig. 4 is a fragmentary detail view illustrating the switch block.

Fig. 5 is an enlarged transverse sectional view taken on the line 5—5 of Fig. 1.

Fig. 6 is a detail sectional view taken on the line 6—6 of Fig. 5.

Fig. 7 is a fragmentary plan view illustrating a modified form for supporting the scoring device.

Fig. 8 is a slightly enlarged sectional view illustrating the split sleeve terminal of the insulating block with the coöperating terminal disposed therein.

Referring now more particularly to the accompanying drawings, the character 10 indicates a plate of relatively thin metal provided with a marginal flange 11 forming a recess 12 on its under side and which flange is offset, as at 13, and recessed at intervals, as at 14, for a purpose presently explained.

In the recess 12, on opposite sides of the plate, are sets of transversely disposed spaced strengthening ribs 15. The ribs of one set are preferably arranged opposite the ribs of the other set with the opposing ribs terminating short of one another to form a longitudinal space in which is located a relatively long longitudinally disposed strengthening rib 16 which is spaced from 110

the aforesaid ribs and whose ends terminate short of the strengthening blocks 17. Supporting elements or feet 18 project from the spaces between the ribs, while supporting elements or feet 19 are formed on the ribs 15 and 16.

The inner faces of the marginal flange and the under side of the plate 10 are coated with non-conducting enamel and flat electrical conductors 20 are disposed one on each side of the aforesaid longitudinal rib 16. Each longitudinally disposed conductor 20 is provided with outwardly directed loops 21 which lie in the spaces between the aforesaid sets of spaced strengthening ribs 15, the purpose of which is to provide for ample heating capacity. The conductors 20 and their loops lie relatively close to the underside of the plate 10 and are connected at one end by a wire 22. At the opposite end a wire 23 leads from one of the conductors to a terminal 24 disposed in the aforesaid offset 13 of the metal plate. In this offset 13 are two other terminals 25 and 26, the terminals 24, 25 and 26 preferably gradually decreasing in cross sectional diameter, as shown. These terminals are adapted to removably receive the respective split sleeve terminal sockets 27, 28 and 29 carried in the insulating block 30 which latter is adapted to fit snugly within the offset 13 with its upper face preferably flush with the upper face of the metal block and to which split sleeves the electric conducting wires 31 is secured so that the current may be conducted through the conductors in the cavity of the metal block and the latter expeditiously and effectually heated. The sockets 27, 28 and 29 carried by the insulating block gradually decrease in size so as to effectually coöperate with the correspondingly formed terminals 24, 25 and 26, by virtue of which the insulating block 30 must be positioned in a certain way in order to operatively connect the terminals.

After the conductors 20 and the electric wires 22 and 23 and the terminals 24, 25 and 26 are positioned, the recess 12 is then provided with a filling, for instance, two, three or more coats of enamel to thereby close up or fill the recess and embed the electrical conductors and wires therein, these last mentioned coatings of enamel completely embedding the strengthening ribs or elements 15, 16 and 17, but exposing the feet or supporting elements 18 and 19. By virtue of these feet or supporting elements 18 and 19 projecting beyond the enamel or other filling material, spaces are provided under the plate so that when the plate is fitted on the bed of a printing press, the heat radiating from the underside of the plate may have passage from between the bed and the plate, the air passing out through the aforesaid recesses 14, whereby

unnecessary heat, instead of being absorbed and retained within the metal plate or between the same and the bed of the printing press, is permitted to pass out through said recesses 14.

70

Transversely disposed dove-tailed grooves 32 are formed in the upper face of the metal plate and extend entirely across the same and also extend into the transverse strengthening ribs 15, opening out through the side edges of the plate.

75

A longitudinally disposed dove-tailed groove intersects these transversely disposed grooves and extends into the aforesaid longitudinal rib 16, extending throughout the length of and through the edges of the plate 10. These dove-tailed grooves render the walls of the transverse and longitudinal ribs comparatively thin, thereby facilitating quick heating of the plate 10, by virtue of heating the air in the channels 32 under the die, incident to the said thin walls.

80

A plate 33 is countersunk in the marginal flange of the metal block 10, one at each end of each of the aforesaid transverse and longitudinal dove-tailed grooves. Each of said plates 33 may be secured in place by means of screws or other suitable fastenings so that they may be connected or disconnected at will in the event of damage or if other occasion requires removal of the plates.

90

Fitted in the transverse groove and in said longitudinal groove are pairs of clamping elements 35 which are adapted to engage the sides and ends of the female embossing die 36 for the purpose of holding the latter firmly on the metal plate 10 for embossing purposes. These clamping elements 35 may be moved to clamping position in any suitable manner. One way in which these clamping elements may be moved to clamping position and loosened or tightened is to provide in each of said grooves a pair of follower blocks 37. Each follower block 37 has a screw threaded bore in which is adapted to operate a screw 38 which is journaled as at 39', in the respective plate 33. On each screw 38 is rigidly secured a turning nut 39 preferably provided with apertures 40 to receive a wrenching device (not shown) to rotate the screw. Upon rotating the screws 38 the respective followers 37 are moved forwardly and backwardly in the respective grooves according to the turn of the nut 39. Interposed between the followers and the respective clamping elements 35 and slideable in the respective grooves are pieces of printer's furniture 41. The size of these pieces of furniture depends upon the size of the female clamping die to be clamped on the plate. It would seem clear, therefore, that upon operating the turning nut, the screws are operated to shift the followers, and consequently the furniture 41, so as to firmly clamp the female die plate 110

on the metal plate 10 and that upon opposite sides of the plate, but in view of the economical furniture and clamping elements 35 may be moved away from the female embossing die so that the latter may be readily removed not ordinarily, if at all, necessary. In any event, by means of a switch (not shown) any two of the three wires 31 may be cut in or out of the electric circuit so that the three circuits of wiring in the heater may be utilized for high, medium and low heating, as may be desired. For instance, for high heating the current may be through the circuit w , when the heater is subjected to the heat of the current. For medium heating the current may pass through the circuit y , when about two thirds of the heating element is included in the circuit. For low heat the current passes through the circuit z , which includes about one third of the heating element.

There are times when it is desired to simultaneously emboss and score, for instance, the cover of a book, and for this reason I provide a scoring device, preferably in the form of a metallic strip 42 which, if desired, may be secured by means of screws or other suitable fastenings 43 to the followers along one side of the heating plate, whereby upon operation of the turning nut 39 this scoring device may be adjusted accordingly toward and away from the female embossing die. Independent adjustment of this scoring device 42 may be had by providing the respective follower blocks with grooves

44. If preferred, the scoring device 42 may be wholly independent of the follower blocks by providing grooves 45 in the heating block and mounting blocks 46 therein which are adapted to slide in the grooves 45, the scoring device 42 being, in such event, secured by means of a screw or other suitable fastening 47 to the blocks 46.

The assembled plate and die have a combined thickness which is just "type-high" or equal to the height of ordinary type which enables the block and die to be used in place of the type on the bed of an ordinary printing press. The block is adapted to be clamped in the chase 48 of the press by means of the ordinary printer's furniture 50 and quoins 51 and the whole mounted on the bed of the press as though it were type. The male die member is attached to the platen of the press and the device is then ready for operation.

This device provides an extremely simple and cheap apparatus for heating embossing dies, there being no waste heat and it being possible to effectually heat the block with a minimum amount of heating medium. The material of which the block is formed is relatively thin, as has been stated, and by virtue of the transverse and longitudinal grooves, the walls of the strengthening ribs are comparatively thin, whereby radiation of the heat is expeditious with a minimum amount of heat. The device is particularly well adapted for heating small dies and may be sold so cheaply that it can be afforded by printers doing comparatively little embossing work who cannot afford to buy the large and expensive machines built expressly for embossing purposes.

If desired, a rheostat may be included in

What is claimed is:

1. An electric heater of the type described comprising a metal plate provided with a marginal flange, opposite sets of transverse ribs arranged on the under side of the plate within said flange, the ribs of each set being spaced from one another and at their inner ends terminating short of the ribs of the opposite set, a longitudinally disposed rib arranged between the sets of transverse ribs and spaced therefrom, electric conductors arranged one on each side of the longitudinal rib, each conductor having looped portions extending outwardly and lying between the transverse ribs, electrical connections between the said conductors, and means whereby an electric current may be supplied to said electric connections to heat the plate.

2. An electric heater of the type described comprising a metal plate provided with a marginal flange, opposite sets of transverse ribs arranged on each side of the plate within said flange, the ribs of each set being spaced from one another and at their inner ends terminating short of the opposite set, a longitudinally disposed rib arranged between the sets of transverse ribs and spaced therefrom, electric conductors arranged one on each side of the longitudinal rib, each conductor having looped portions extending outwardly and lying between the transverse ribs, electrical connections between the said conductors, and means whereby an electric current may be supplied to said electric connections to heat the plate.

3. An electric heater of the type described comprising a metal plate provided with a marginal flange, electric conductors adjacent the plate within said marginal flange, said conductors having projecting looped portions, electric connections between said conductors, means whereby current may be supplied to said electric connections to heat

the plate, and said marginal flange having recesses to provide passages for the escape of heat from under the plate.

4. An electric heater of the type described, a metal plate provided with a marginal flange having an inwardly directed off-set, opposite sets of transverse ribs arranged on the underside of the plate within said flange, the ribs of each set being spaced 10 from one another and at their inner ends terminating short of the ribs of the opposite set, a longitudinally disposed rib arranged between the sets of transverse ribs and spaced therefrom, electric conductors

arranged adjacent the longitudinal rib, each having looped portions extending between the transverse ribs, electrical connections between the said conductors, terminals mounted in the off-set of the marginal flange, and an insulator-block adapted to fit in said off-set and carrying terminals for electrical connection with the aforesaid terminals. 15 20

In testimony whereof I affix my signature in presence of two witnesses.
